UNITED STATES PATENT OFFICE

EDWIN RUUD, OF PITTSBURGH, PENNSYLVANIA, ASSIGNOR TO RUUD MANUFACTURING COMPANY, OF PITTSBURGH, PENNSYLVANIA, A CORPORATION OF NEW JERSEY.

REFRIGERATING APPARATUS.

1,153,712.

Specification of Letters Patent. Patented Sept. 14, 1915.

Application filed May 6, 1912. Serial No. 695,432.

To all whom it may concern:

Be it known that I, EDWIN RUUD, a resident of Pittsburgh, in the county of Allegheny and State of Pennsylvania, have invented certain new and useful Improvements in Refrigerating Apparatus, of which the following is a specification.

The primary object of the invention is to provide a fully automatic refrigerating apparatus of absorption type that requires no attention after being installed and started, the apparatus being caused to repeat its cycle of operations automatically by the substance that causes refrigeration. Attention and care of an operator are unnecessary, the apparatus being self-contained and self-operated.

A further object of the invention is to provide for automatically controlling the temperature of the refrigerator, refrigeration being stopped when the desired degree of cold is attained, so that it is quite impossible for freezing or damaging low temperatures to be created within the refrigerating compartment.

Still a further purpose is to provide two separate controlling means for the gas supply, one being controlled by the substance that causes refrigeration, and the other by the temperature of the generator, so that the supply of gas will be diminished or cut off when the generator has attained a sufficiently high temperature before the product of the generator has accumulated in sufficient amount to operate the gas valve mechanism controlled thereby.

In the accompanying drawings, Figure 1 is a diagrammatic illustration of the apparatus, the several parts being in the position they assume when the generator is in action and before it begins to act as an absorber. Fig. 2 is a view similar to Fig. 1, showing the several parts in the positions they assume when refrigeration is going on, with the generator shut off, and with the generator-absorber acting as an absorber. Also included in Fig. 2 are several features of modified construction.

Referring to the drawings, 2 is the tank or container which initially serves as a generator and subsequently as an absorber, the former when the burner or heater is active for generating ammonia vapor and gas, and operating as an absorber when the depleted

liquid remaining therein following the generating process is reabsorbing the ammonia after it has accomplished refrigeration. A vapor and gas outlet pipe 3 extends from the top generator 2 to separating coil 4 immediately above and connected to condenser coil 5. Coil 4 serves to separate the initial condensate from the gas and drains it back into the generator, while the substantially pure ammonia gas and vapor pass into the condenser coil.

The lower end of condenser coil 5 connects with a tank-like receiver 6 which is movable vertically with its supporting lever 7, the latter fulcrumed at 8 and carrying counterweight 9. A fixed stop 10 extends between lugs 11 and 12 projecting from receiver 6, said stop and lugs limiting the upward and downward movement of the receiver. Counterweight 9 is adapted to shift or roll on lever 7 between stops 7' and 7''. When container 6 is elevated as in Fig. 1 the lever is inclined sufficiently to cause the weight to shift outwardly against stop 7' and exert maximum resistance to the lowering of receiver 6. But when the latter fills sufficiently to overcome the weight and lower, the weight shifts inwardly against stops 7'', as in Fig. 2, thereby decreasing the leverage and permitting the receiver to remain in lowered position until empty or approximately so.

Connected to the bottom of receiver 6 is coil 13 of pipe 14 which extends to the refrigerator 15, where it connects with the refrigerating coil 16 in manner presently to be explained. In the adaptation shown in Fig. 1, a thermostatic valve 17, mounted in the end of generator 2, is interposed in pipe 14 and controls the flow from receiver 6 to the refrigerating coil, as will presently appear. In the adaptation of Fig. 2, valve 17 is omitted, pipe 14 extending uninterruptedly from receiver 6 to the refrigerator.

At the refrigerator, pipe 14 connects with the thermostatic valve 18 which is controlled by the temperature of the refrigerating chamber and governs the admission of the refrigerating substance into the refrigerating coil 16. The refrigerating coil or pipe 16 is connected by pipe 19 to the absorber, the flow therethrough being controlled by check valve 20 which opens toward the absorber. A similar valve 21 in pipe 3 opens

away from the absorber and prevents backward discharge into the absorber from the condenser.

The generator heating means consists of a gas burner 22 to which gas is supplied through pipe 24 in which is interposed valve 25. Stem 26 of this valve is adjustably connected to one end of lever 27 fulcrumed between its ends and at its opposite end connected to snap spring 28. A link 29 connects lever 27 with the counterweighted end of the receiver-supporting lever 7. A bracket 30 provides a convenient support for levers 7 and 27, also for valve 25, and one end of the bracket may be shaped as shown to provide the stop 10. The outer end of snap spring 28 may be connected to a downward extension 30' of the bracket.

In the preferred arrangement, gas supply pipe 24 is provided with a thermostatic valve 32 fixed in the end of container 2 opposite valve 17, valve 32 proportioning the flow of gas to the temperature of the liquid in the container, the action of the thermostat being such as to contract the gas passage as the temperature rises and to cut off the gas altogether when the desired maximum temperature has been attained.

33 is a constantly burning pilot for burner 22. Container 2 may be provided with a pressure gage 34 and thermometer 35.

In operation, generator 2 is nearly filled with water and ammonia, the proportions as commercially obtainable being about one-third ammonia and two-thirds water. With the parts in the position shown in Fig. 1, gas valve 25 is open, and the liquid being cold or relatively cool thermostatic valve 32 is also open. Receiver 6 is empty, or substantially so, and is in elevated position with lug 11 engaging stop 10. Under these conditions generator 2 and its contents are gradually heated, and as the temperature rises ammonia vapor and gas are generated, and under the increasing pressure the vapor and gas pass off through pipe 3 into separator 4 which results in draining the initial condensate back through pipe 3, and substantially pure ammonia gas, or vapor or both, are delivered through check valve 21 into the condenser coil 5 where, under proper temperature and pressure conditions, the gas and vapor are liquefied, the liquid discharging into receiver 6. This operation will continue until practically all of the ammonia has been extracted from the liquid in generator 2, when the weight of the accumulated liquid ammonia in receiver 6 overcomes counterweight 9 and the receiver lowers to the position shown in Fig. 2 with lug 12 engaging stop 10, the convolutions of condenser coil 5 and coil 13 being sufficiently flexible to permit of the vertical movement of the receiver without hindrance. The counterweighted end of lever 7 is of course

elevated as the receiver lowers, and through link connection 29 burner controlling lever 27 is oscillated and gas supply valve 25 closed. Snap spring 28 is so arranged that initially it opposes the movement of lever 27 in either direction and accelerates the last portions of each of said movements, the spring being contracted by such initial movements and expanding during the completion of such movement. Link 29 is slotted vertically at 31 to receive connecting pin 31' of lever 7. Normally, pin 31' is approximately midway the ends of the slot, whether the mechanism is holding valve 25 open, as in Fig. 1, or closed as in Fig. 2. Slot 31 permits lever 7 to move either up or down through the major portion of its throw without affecting the gas valve, the latter being closed or opened by a sudden and complete movement instead of closing or opening gradually as receiver 6 lowers or raises, the movement being accelerated, as above indicated, by spring 28. This insures positive predetermined action from the burner, prevents injury thereto resulting from gradual increase and decrease of heat, and avoids flickering or variation in the flame. With receiver 6 in lowered position and the gas shut off from burner 22 generator 2 cools down to a point where the depleted liquid or "poor liquor" will absorb ammonia vapor, whereupon the generator becomes an absorber. The arrangement is preferably such that thermostatic valve 17 remains closed until the liquid is some degrees below the point at which absorption will begin. But when the temperature has lowered sufficiently to open valve 17 the liquid ammonia from receiver 6 is permitted to flow through pipe 14 and into the normally open thermostatic valve 18 and into refrigerating coil 16 where cold is developed due to the expansion and vaporization of the liquid, valve 18 being in effect an expansion valve. The ammonia vapor, with the heat absorbed from refrigerator 15, is conducted through pipe 19 into chamber 2 which, as before stated, has now become an absorber, the vapor flowing past check valve 20. This absorption process continues until all of the liquid is absorbed from receiver 6, or until the temperature of refrigerator 15 is reduced as low as desired, determined by the adjustment of valve 18. If the minimum temperature is reached before tank 6 is emptied and hence before it rises from the position shown in Fig. 2 to that of Fig. 1, valve 18 closes and the circulation is shut off, and the apparatus remains at a standstill until the temperature of the refrigerator rises sufficiently to open valve 18 for the continuation of the refrigerating and absorbing processes and until receiver 6 is relieved of enough of its contents to be counterbalanced by weight 9, whereupon the

receiver rises and the parts resume the positions shown in Fig. 1 which results in opening gas valve 25 and starting burner 22 and again heating up the rehabilitated liquid 5 in generator 2. The pressure in the generator soon overcomes the pressure in pipe 19 and closes check valve 20, and the absorber is transformed into a generator and so continues until substantially all of the ammonia is again extracted from the liquid in container 2. When the liquid within the container attains a sufficiently high temperature for the generating process the supply of gas will be diminished or cut off, as the case 15 may be, by thermostatic valve 32 which is adapted to fully close when the liquid has attained a given maximum temperature. The dual gas supply control, viz., valves 25 and 32, are quite important. Valve 25 acts 20 positively to shut off the supply at the completion of the generating process, and valve 32 either diminishes the supply or cuts it off altogether when the liquid has attained a sufficiently high temperature before the 25 completion of such generation, thus preventing the generator from becoming overheated.

I use the term refrigerating coil in its broad sense, meaning thereby any form of conduit for the vapor that will accomplish 30 refrigeration regardless of whether located within a refrigerating chamber or wherever it is desired to accomplish refrigeration. In the embodiment here shown, the stem-like extension of valve 18 is embraced by 35 the refrigerating coil so that when the refrigerator attains the desired minimum temperature the valve is closed and refrigeration stops until the temperature rises sufficiently to open it. By this means the 40 refrigerating process is so controlled that it is absolutely impossible for the refrigerator to attain a damaging low temperature.

While I prefer to provide two separate means for controlling the flow of liquid 45 ammonia to the refrigerating coil, viz., valves 17 and 18, valve 17 may be dispensed with, as in Fig. 2, the flow being controlled entirely by valve 18 which, in turn, is directly controlled by the temperature of the 50 refrigerator.

In lieu of thermostatic valve 32 for the gas supply, the valve mechanism shown in Fig. 2 may be employed wherein valve 40 in gas pipe 24 is held normally open by spring 55 41 which bears against diaphragm 42 to which pressure from generator 2 is communicated through pipe 43, with the result that when sufficiently high pressure has been attained spring 41 is compressed and valve 40 partially or completely closed, as determined by the pressure.

The operation of the apparatus as shown in Fig. 1 presupposes such atmospheric conditions as will cool the condenser coil 5 sufficiently to perform its function, and like-

wise will sufficiently cool chamber 2 to constitute it an absorber. However, climatic conditions or the normal temperature of the compartments in which the apparatus is located may be too high to be effective. In 70 such case, the expedient illustrated in Fig. 2 may be resorted to in which a considerable portion of the chamber coil is inclosed in a water tank 44, enough of the coil convolutions remaining beneath the tank to compensate 75 for the vertical movement of receiver 6. 45 is a water supply pipe which delivers to the double acting valve 46 from which leads a pipe 47 to tank 44 and another pipe 48 into chamber 2, being preferably 80 coiled therein as indicated at 49 and leading therefrom at 50. 51 is the overflow pipe for tank 44. By this arrangement when chamber 2 is acting as an absorber the double valve 46 is closed to pipe 47 and open to 85 pipe 48 so that water circulates through coil 49 and assists very materially in lowering the temperature of the depleted liquid remaining in chamber 2, thereby increasing its efficiency as an absorber. As valve 46 is 90 operated conjointly with gas valve 25, the opening of the latter, as in Fig. 1, will close valve 46 to pipe 48 and open it to pipe 47 thereby establishing circulation of water 95 through tank 44 and increasing the efficiency of the condenser. The cooling effect of the water is transmitted alternately to the condenser and to the generator-absorber, these effects alternating with the alternations of the apparatus from generating and condensing to refrigerating and absorbing, as will be understood.

The thermostatic valves 17, 18 and 32, the gas valves 25 and 40, and the water valve 46, are all old and well known to those 105 skilled in the art and detailed illustration and description are believed unnecessary.

While it is designed primarily that refrigeration shall take place only when the parts are in the positions or adjustments 110 shown in Fig. 2, or in other words when chamber 2 is operating as an absorber, the cold produced during such alternating periods is ordinarily sufficient to maintain the refrigerator at sufficiently low temperature 115 during the generating and condensing period, but if necessary a receptacle containing brine may be placed within the refrigerator, or other means may be employed for storing up the cold and giving it off 120 when the refrigerating coil cannot be active.

I refer herein to the use of ammonia because its properties are well known, and because it is generally used in refrigerating plants. It will be understood, however, that 125 any other fluid having like or similar characteristics may be employed without departing from the invention.

I claim:

1. Refrigerating apparatus comprising a

generator, an upright flexible condenser coil connected thereto, a vertically movable receiver to which the flexible coil is connected, counterweight means sustaining the receiver 5 normally elevated but adapted to be overbalanced and the receiver depressed by liquid accumulated in the receiver, a heater for the generator, heater controlling means movable with the receiver, and a refrigerating coil adapted to communicate with the receiver and with the generator.

2. Refrigerating apparatus comprising a generator, a condenser connected thereto, a refrigerator, a refrigerating coil adapted to 15 communicate with the condenser and with the generator, thermostatic valves exposed respectively to the generator and the refrigerator for controlling the passage of fluid from the condenser to the refrigerating coil, and condenser heating means.

3. Refrigerating apparatus comprising a generator, a condenser, a refrigerating coil adapted to communicate with the refrigerator and with the condenser, a gas burner 25 for the generator, a gas supply pipe leading to the burner, two valves controlling the flow of gas to the burner, means actuated by the condition of the generator contents for actuating one of the valves, and means actuated 30 in part by the product from the condenser and in part by a counterweight for actuating the other of said valves.

4. Refrigerating apparatus comprising a generator, a condenser, a refrigerating coil 35 adapted to communicate with the condenser and with the generator, a gas burner for the generator, and two independent automatically operated valves for controlling the flow of gas to the burner, one valve actuated 40 by the liquid in the generator and the other valve by liquid from the condenser.

5. Refrigerating apparatus comprising a generator, a condenser communicating therewith consisting of an upright flexible coil, 45 a vertically movable receiver connected to the lower end of the condenser, a refrigerating coil, a pipe coiled adjacent to the receiver and connected to the latter and to the refrigerating coil and adapted to compensate for the vertical movement of the receiver, a counterweighted support for the

receiver, a heater for the generator, and heater controlling means movable with the receiver.

6. Refrigerating apparatus comprising a generator, a condenser connected thereto, a vertically movable receiver into which the condenser discharges and which is depressed by liquid accumulated therein, means for restoring the receiver to raised position when depleted of liquid, a heater for the generator, heater controlling means having a loose connection with the receiver and actuated only by the last portions of the opposite vertical movements of the receiver to start and stop the heater, and a refrigerating coil adapted to communicate with the receiver and with the generator.

7. Refrigerating apparatus comprising a generator, a condenser connected thereto, a vertically movable receiver into which the condenser discharges and which is depressed by the weight of liquid accumulated therein, means opposing depression of the receiver and for elevating it when depleted of liquid, 75 a heater for the generator, a refrigerating coil adapted to communicate with the receiver and with the generator, and a thermostatic valve exposed to the temperature of the refrigerating coil and controlling the 80 passage of fluid into the latter from the condenser.

8. Refrigerating apparatus comprising a generator, a condenser connected thereto, a vertically movable receiver into which the condenser discharges and which is depressed by the weight of liquid accumulated therein, means opposing depression of the receiver and for elevating it when depleted of liquid, 85 a heater for the generator, a refrigerating coil adapted to communicate with the receiver and with the generator, and a thermostatic valve exposed to the temperature of the generator for controlling the passage of fluid from the condenser to the refrigerating coil.

In testimony whereof I affix my signature in presence of two witnesses.

EDWIN RUUD.
